UNITED STATES PATENT OFFICE.

ELLIS J. G. PHILLIPS, OF AURORA, ILLINOIS. ASSIGNOR TO RICHARDS-WILCOX MANUFACTURING COMPANY, OF AURORA, ILLINOIS, A CORPORATION OF ILLINOIS.

TROLLEY TRACK.

Application filed March 23, 1922. Serial No. 545,962.

To all whom it may concern:

Be it known that I, ELLIS J. G. PHILLIPS, a citizen of the United States, and a resident of Aurora, in the county of Kane and State of Illinois, have invented certain new and useful Improvements in Trolley Tracks, of which the following is a specification, reference being had to the accompanying drawings.

10 This invention relates to improvements in double-rail trolley tracks primarily designed for use in connection with sliding doors that are adapted to close a doorway in a wall of a building and which are also adapted to be moved when not in use to a position alongside of another wall that stands at right angles to the wall that has the doorway. The two sections of overhead track that lie adjacent to such two walls are 15 of course connected by a curved track section so as to form a continuous path for the wheels of the carriages that travel on the two rails of the track and from which carriages the door is suspended. It is very desirable, 20 of course, that such curved connecting track section or corner portion should have as short a radius as possible, not only to allow the door to be brought conveniently close to either wall without undue length of travel 25 of the said wheeled carriages but also so that said curved connecting section shall not extend out into the room to any great extent and thereby constitute a disfigurement and also a possible obstruction to the moving of certain tall articles in or adjacent to 30 the corner of the room where such curved connection is located. The side walls of the curved connection have heretofore been spaced apart to the same extent as the two 35 main straight track sections that connect with it and the result has been that as the carriages passed through it their wheels would, by reason of the short radius of that section of the track, come into grinding 40 contact with the side walls thereof and seriously interfere with the easy movement of the door from one of its said positions to the other. Various expedients have been devised to obviate this objection, among which 45 may be cited the construction shown in Letters Patent No. 1,188,482, granted June 27, 1916, upon an application filed by me. While the construction there shown has been found satisfactory it involves considerable more expense that is desirable in connection with

the installation of doors in some situations, owing to the addition to the wheeled carriages of extra parts.

It is the object of my present invention to remedy the objection mentioned by improvements in the track itself rather than in the wheeled carriages that run thereon; and, briefly and broadly stated, I accomplish this by making the curved connecting member of the track wider than the straight track sections that connect therewith (except the end portions of such straight sections that abut against the ends of the curved section) and forming such straight sections slightly tapering from end to end so that at their inner and wider ends they will accurately register or align, respectively, with the ends of the wide curved corner section, all as shown in the drawing and more particularly described hereinafter.

In the drawing,—

Fig. 1 is a top view, partly in horizontal section, of a trolley track embodying my invention;

Figs. 2 and 3 are vertical cross-sections taken respectively on the lines 2—2 and 3—3 of Fig. 1; and

Fig. 4 is a longitudinal vertical section taken on the line 4—4 of Fig. 3.

Referring to the several figures of the drawings, 5 indicates a curved track section adapted to be located adjacent to the corner of a room and constituting a portion of a track that extends along opposite two walls of a room in one of which will be formed a doorway adapted to be closed by a sliding door, and against the other wall which stands at right angles thereto such door is adapted to be moved when the doorway is uncovered. This curved track section 5 in the construction shown (see Fig. 3) is formed of two side walls 5^a placed a distance apart and parallel with each other, the lower marginal portions of which are bent inward and upward to form ordinary rails for the wheels of a carriage to run upon, and the upper marginal portions of which walls are inwardly turned and connected together, such connection in the construction shown being by an overlying piece 105 of sheet metal 5^b spot-welded thereto. The track structure described is of ordinary form in cross-section except that such tracks are usually formed from a single piece. On account of the curvature such 110

corner pieces of this cross-section are ordinarily formed by casting, but by making the two wall members 5^a separately and connecting them together by the plate 5^b I am able to make them without difficulty of sheet metal as in the case of straight sections of track, which is of considerable advantage as the structure is, of course, lighter and the track as a whole is more uniform in appearance than where one part is a casting and the other parts are of sheet metal. This curved section 5 is intended to be wider than the straightaway sections that connect with it in order that more room may be provided for the wheels, and thereby avoid the liability so common in corner sections of short radius of having the edges of the wheels contact with and grind against the side walls or against the upturned lips of the rails, or both. 6 indicates a straightaway section of track which in cross-section is substantially like the curved section, but, as clearly shown in Fig. 2, is made from a single piece of sheet metal, as is usual. The only departure from ordinary practice in the construction of such track section 6 is that it is made gradually tapering throughout its length so that at its inner and larger end it is of a width to abut against and register or aline with the ends of the curved section 5. At its other and smaller end it is of the same width that track of this description is ordinarily made so that if another section of track of said ordinary width is connected with it, as is here shown to be the case, the abutting ends will aline or register as usual. Such an additional track section as last referred to is indicated by 7. The tapering of the track section 6 is formed by making the bends at the upper and lower ends of the side walls of the two parts 5^a—5^a along slightly diagonal lines instead of along parallel lines as in the case of the forming of an ordinary track section such as that indicated by 7. The bending up of the lips at the inner edges of the two rails of the track will be along parallel lines, as usual, so that such rails will remain throughout the length of the tapered sections evenly spaced apart as usual.

A tapered section 6 will abut against each end of the curved corner section 5, of course, and, while it is possible to make such tapered sections long enough to constitute the straightaway portions of the track in and by themselves, yet it will be found better practice to use such tapered sections only as means interposed between the curved corner section and a section of the usual width such as indicated by 7. Ordinary sustaining brackets adapted to be secured against a wall will be applied to the track. In the construction shown two brackets 8 are indicated as supporting the adjacent

end portions of the curved section 5 and the tapered sections 6, such brackets being of the usual construction except that they will be given a slight taper to make them conform to the tapering end of the section 6 so as to thereby hold the abutting parts snugly in proper alined position. Other brackets, such as 9, are shown for connecting together the abutting ends of the sections 6 and 7, and they will, of course, also be properly shaped to snugly receive and hold such ends. To prevent endwise movement that would allow withdrawal of a track section from its supporting bracket I preferably indent the upper wall of the track as at 10, into which indentations the ends of bolts 11 pass, such bolts being screw-threaded through the upper walls of the brackets.

By my invention I provide a track that incorporates in it at the bend a short radius section of a materially wider width than is ordinarily provided, and which, therefore, allows a free sidewise turning of the wheels of a carriage on the track without such wheels being hampered in their rolling movements by hard scraping against the sides of the section or the upturned lips at the inner edges of the track. Furthermore, by making the section 6 of the track tapering as described I am able to provide a construction wherein notwithstanding the difference in width between the curved piece and the straight sections of ordinary size I am able to connect these several parts together in such manner as to preserve the good appearance of the track as a whole and at the same time provide for the perfect connection of the several sections of the track so as to insure the easy running of wheeled carriages thereon.

What I claim as my invention and desire to secure by Letters Patent, is—

1. In a trolley-track, the combination of a curved track section and another section that abuts at one end against an end of the curved section, each of said sections comprising a wall member and a rail member, the rail member of the curved section being materially wider throughout its length than the rail member of the other section to obviate binding of the wheels of a trolley against the wall of the curved section when a trolley is moving therealong.

2. In a trolley-track, the combination of a curved track section and another section that abuts at one end against an end of the curved section, each of said sections comprising a wall member and a rail member, the rail member of the curved section being materially wider throughout its length than the rail member of the other section to obviate binding of the wheels of a trolley against the wall of the curved section when a trolley is moving therealong, and the rail member of said second-named section gradually de-

creasing in width from the end adjacent to the said curved section.

3. A double-rail hollow trolley-track comprising in combination a curved section and a tapering section abutting at its larger end against one end of the curved section.

4. A double-rail hollow trolley-track comprising in combination a curved section, a straight section of less width than the curved section, and a tapering section intermediate said two first-named sections.

5. A double-rail hollow trolley-track comprising in combination a curved section and another track section having one of its ends

of substantially the same width as the width 15 of the curved section and against which curved section said end abuts, the opposite end of said second-named section being of less width than the curved section.

6. A curved double-rail hollow track sec- 20 tion comprising in combination two spaced-apart sheet-metal wall members having inwardly-turned marginal rail portions and inwardly-turned upper marginal portions, and a plate secured to said upper turned por- 25 tions to hold said wall members together.
